UNITED STATES PATENT OFFICE

2,526,170

FRICTION SASH HOLDER

George Steingruber, Atlanta, Ga.

Application October 21, 1948, Serial No. 55,759

18 Claims. (Cl. 292—70)

1

The present invention relates to sash holders for vertically sliding window sashes, and more particularly, to an improved sash holder of the friction type which will effectively support the sash in any position of vertical adjustment, without the aid of sash weights or other counterbalancing means, yet which permits the sash to be raised or lowered, as desired, with ease.

The primary object of the invention is to provide a simple and inexpensive sash holder which may be used with sliding sashes and frames of practically any construction, whether of wood, metal or other materials, and which may be easily installed, either at the time the window structure is originally assembled, or subsequently thereto, as for existing windows to eliminate the usual counterweights, stops or other counterbalancing or holding means.

A further object of the invention is to provide a sash holder of the friction type which may be attached to the top or bottom edge of the sash, as the circumstances require, and which, when so attached, fits within the sash channel of the window frame in which the sash is slidably mounted, said holder including a pair of friction shoes, one of which is fixed, and the other of which is movable and spring-pressed to normally yieldingly urge the latter shoe away from the fixed shoe and into frictional engagement with the sash channel.

A still further object of the invention is to provide a sash holder which includes a friction shoe which is pivotally mounted for self-aligning engagement with the sash channel of the window frame, and which is normally yieldingly urged into engagement therewith, said friction shoe being so supported that it acts to create a limited binding action against the sash channel to an extent sufficient to support the weight of the sash, but still permitting the sash to be moved in a downward direction by the application of a relatively small force thereto, while freely yielding to release the binding action when the sash is moved in an upward direction.

Another object of the invention is to provide a sash holder of the aforementioned friction type which is easily adjustable to regulate its frictional force and binding action as required for windows of different sizes and/or weights, and according to the desired ease with which the sash may be raised or lowered.

Other and further objects and advantages of the invention will be hereinafter described and the novel features thereof defined in the appended claims.

2

In the drawing:

Figure 1 is a view in front elevation of a window structure of the double-hung sash type, with certain portions of the window structure broken away and shown in section to expose the sash holders for the respective sashes, according to the present invention;

Figure 2 is a vertical sectional view on an enlarged scale, as taken on the line 2—2 of Figure 1, and showing the respective sash holders in side elevation and in more detail;

Figure 3 is a horizontal sectional view, also on an enlarged scale, as taken on the line 3—3 of Figure 1, through the sash holder for the lower sash; and

Figure 4 is a vertical sectional view as taken on the line 4—4 of Figure 2, through the sash holder for the lower sash.

Like reference characters designate corresponding parts in the several figures of the drawing, wherein 1 generally denotes a window frame having a pair of window sashes slidably mounted therein for vertical movement thereof, the lower sash being indicated at 2 and the upper sash at 3. Both the window frame 1 and the sashes 2, 3, have been shown for purposes of illustration herein as a typical, conventional window structure or assembly as commonly employed for window structures of wood, but it is to be understood that the present invention is not confined to such specific structures since it is equally applicable to window structures of metal or other materials, and the details of which may differ materially from those referred to herein for illustrative purposes.

According to the drawing, the window frame 1 is provided at its opposite sides with vertically extended stop strips or members 4 arranged at the inner and outer faces respectively of the window frame, together with an intermediate parting strip 5, also vertically extended, at each side of the frame. The stop strips 4 and the intermediate parting strip 5 thus define a pair of channels, respectively designated 6 and 7 at each side of the window frame 1, for slidably receiving the window sashes therein, the upper sash 3 being slidably mounted in the channels 6, and the lower sash 2 being slidably mounted in the channels 7.

As customary in double-hung window structures of this type, the lower sash is provided at its upper horizontal edge with a meeting rail 8, and the upper sash is provided along its lower horizontal edge with a corresponding rail 9, said meeting rails 8 and 9 closely abutting against

each other when the lower sash 2 is moved downwardly to the limit of its downward movement against the sill 10 of the frame 1, and when the upper sash 3 is raised to the limit of its upward movement to fully close the same against the head 11 of the window frame.

In order to support the respective sashes 2 and 3 in any position of their vertical adjustment in the window frame 1, as desired when either sash is in a partially or fully opened position, I provide a sash holder for each sash, as generally indicated at 12 and 13, each sash holder being anchored to its sash near one edge of the same, and fitting in the sash channel of the window frame 1 in which the sash is slidable.

In the case of the lower sash 2, the sash holder 12 is attached to the upper horizontal edge of the sash near one end of the same, and in the case of the upper sash 3, the sash holder 13 is attached to the lower horizontal edge of the sash, preferably near the opposite end of the latter, as generally shown in Figure 1 of the drawing. However, this arrangement is not critical and may be changed if preferred, as will be obvious from the following description.

Referring now more particularly to the details of the sash holder 12 for the lower sash 2, it will be seen that the holder includes a vertically extended plate of metal or other suitable rigid material, which is somewhat narrower than the width of the sash channel 7 in which the sash 2 is slidably mounted. At the bottom of this plate 14, the plate is provided with an inwardly extended ear or foot 15 which is disposed perpendicularly to the plate 14 and is provided with an opening therethrough for loosely receiving a suitable anchoring member, such as a screw 16, nail, or the like, which is driven into the upper horizontal edge of the sash 2. At its upper end, the plate 14 is provided with an outwardly extended flange 17, disposed perpendicularly to the plate 14, the extreme outer edge of said flange being preferably spaced slightly from the bottom of the sash channel when the sash holder is mounted on the sash 2, so that the flange will not rub or scrape against the window frame.

Mounted on the outer face of the plate 14 along one edge thereof is a fixed friction shoe 18, said friction shoe being composed of any suitable frictional material, such as wood, metal, plastic, fiber, hard rubber, or the like. I have found, however, that a material known as "Graphite Celeron" is particularly useful for the purposes of the present invention, since it is relatively inexpensive, easy to shape and machine, has the desired friction qualities, and operates with a smooth sliding action. Anchoring of the shoe 18 to the plate 14 may be accomplished in any suitable manner, as by means of two or more screws 19. It will be observed that when the shoe 18 is fixed or anchored to the plate 14, one of its vertical edges is extended beyond the corresponding vertical edge of the plate 14 so that the overhanging or extended edge of the shoe is free to engage against the adjacent face of the parting strip 5, thereby presenting a flat surface of substantial area so as to create sufficient friction when in contact with the parting strip 5, as necessary to sustain the weight of the window sash when the sash holder is mounted thereon.

The edge of the fixed shoe 18 opposite to the overhanging edge above referred to is preferably slotted as indicated at 20, and one end of a link 21 is inserted in the slot 20 and is pivotally fixed

to the shoe 18, as by means of a pin or rivet 22. The opposite end of the link 21 is inserted in a corresponding slot 23 which is formed in a second shoe 24 which may be identical with the fixed shoe 18, except that the shoe 24 is free to float on the end of the link 21 to which the shoe is pivotally connected by means of a second pin or rivet 25. The link 21 is of such length that the edge of the shoe 24 opposite to the slotted edge is always extended substantially beyond the corresponding edge of the plate 14, so that the floating shoe 24 is always free to self-align itself in parallel relation to the shoe 18 when frictionally engaged with the adjacent vertical face of the stop strip 4 at the side of the channel 7 opposite to the parting strip 5.

In order to yieldingly urge the floating shoe 24 into frictional contact with the stop strip 4, and to cause both shoes to bear against the opposite sides of the sash channel 7, a spring 26 is provided, one end of said spring bearing against the intermediate portion of the link 21, and the opposite end of the spring being held and seated in a bracket 27 suitably anchored, as by a screw 28, to the plate 14, or otherwise formed on the plate for holding the spring 26 in an operative position. As observed in Figure 2 of the drawing, the spring 26 normally tends to urge the link 21 in a clockwise direction about the axis of pivotal connection of the link with the fixed shoe 18, thereby tending to move the floating shoe 24 away from the fixed shoe 18. This movement of the floating shoe 24 may be limited by an adjusting screw 29 which is threadedly engaged in an opening in the flange 17 at the upper edge of the plate 14, with the lower end of the screw abutting against the upper end of the floating shoe 24. By appropriately adjusting the screw 29, the yielding action of the spring 26 may be limited to the extent desired for holding the window sash 2 in any position of its vertical adjustment in the window frame, yet permitting the sash to be moved downwardly by the application of an additional force manually applied to the sash in a downward direction. The pressure of the spring 26 upon the link 21, and consequently upon the floating shoe 24 is assisted by the friction action created by the shoes 18 and 24, and more particularly by the floating shoe 24, which tends to urge the shoes against the vertical faces of the sash channel 7 with a more or less wedging action, as permitted by the screw 16 which is loose enough to allow the holder to adjust itself so that both shoes will engage the sash channel. Were it not for the adjusting screw 29, the heavier the window sash, or the harder the force applied downwardly to the sash, the greater would be the wedging action. However, the wedging action can be finally controlled by screwing in or by backing out the screw 29, as the circumstances require, sufficiently to limit the wedging action, by limitation of upward movement of the floating shoe 24, to a degree sufficient to just balance the window sash against its own weight, while permitting the sash to be moved downwardly, when desired, with ease, by the application of a light downward pressure on the window sash.

As the sash 2 is raised, it will be clear from reference to Figure 2 of the drawing that the frictional drag on the floating shoe 24 will cause the latter shoe and the left-hand end of the link 21 to move downwardly slightly, thus releasing the binding or wedging action of the shoes, and permitting the sash to be moved upwardly with

ease. As soon as the upward movement of the sash is discontinued, the force of the spring 26 will again become effective to relatively spread the shoes apart, thus re-establishing the wedging or binding action of the shoes to hold the sash firmly in the position to which it has been raised. It is important at all times that the entire holder assembly be free to adjust itself in the sash channel so that both shoes 18 and 24 will engage the opposite sides of the sash channel. Hence the fastening screw 16 should not be screwed up so tightly as to prohibit lateral movement of the holder assembly, as permitted by making the screw opening through the foot 15 slightly larger than the screw 16.

The holder assembly 13 for the upper sash 3 is substantially identical with the holder assembly 12 previously described, and hence the component parts of the holder 13 have been indicated in the drawing by the same reference characters as for the component parts of holder 12, but the reference characters have been primed in the case of holder 13. The primary difference between the holder assembly 12 and the holder assembly 13 resides in a slightly different arrangement of the adjusting screw which is indicated at 30 in the holder assembly 13. In this instance, the adjusting screw 30 loosely extends through an opening 31 in the flange 17, and the upper end of the screw 30 is threadedly engaged in a threaded opening in the adjacent end of the floating shoe 24'. Thus, by appropriately adjusting the screw 30, upward movement of the floating shoe 24' under the force of the spring 26' may be limited to the extent desired for creating only sufficient frictional engagement of the respective shoes with the opposite sides of the sash channel 6 as to just support the weight of the sash 3, while permitting the sash 3 to be easily lowered, and without causing too great a jamming or wedging action of the shoes as would otherwise occur by the frictional drag on the shoe 24' tending to urge this shoe in an upward direction and hence away from the fixed shoe 18', were it not for the presence and limiting action of the screw 30. Of course, in raising the upper sash 3, the floating shoe 24' will freely move downwardly against the force of the spring 26' so as to release the binding or wedging action of the shoes, as permitted by the freedom of movement of the screw 30 through the opening 31. Generally speaking, the action of the sash holder 13 is identical with that of the sash holder 12.

It will be understood that while only a single sash holder has been shown in the drawing for each sash, two holders may be used for each sash, if desired, one at each side of the sash to fit in the respective sash channels at the opposite sides of the window frame 1. Ordinarily, however, one sash holder for each sash is sufficient, and will work effectively and smoothly as the sashes are raised and lowered.

While the specific details have been herein shown and described, the invention is not confined thereto as changes and alterations may be made without departing from the spirit thereof as defined by the appended claims.

I claim:

1. A window sash holder of the class described for sashes mounted for vertically sliding movements in the usual sash channels of a window frame, comprising a supporting frame adapted to be connected to a horizontal edge of the sash adjacent to one end thereof so as to lie within

the sash channel at the corresponding side of the window frame, a pair of friction shoes mounted on said supporting frame for relative movement of one of said shoes towards and away from the other of said shoes, and means including a link pivotally connecting said friction shoes for normally yieldingly urging said shoes away from each other and into frictional engagement with the opposite faces of the sash channel so as to hold the sash in any position of vertical adjustment in the window frame, with one of the shoes free for relative movement towards the other so as to release the holding effect responsive to raising of the sash.

15 2. A window sash holder as defined in claim 1, wherein one of the friction shoes is fixed to the supporting frame.

3. A window sash holder as defined in claim 1, wherein the sash holder includes stop means for 20 limiting relative movement of the shoes away from each other.

4. A window sash holder as defined in claim 1, wherein the sash holder includes adjustable stop means for limiting relative movement of the 25 shoes away from each other.

5. A window sash holder for window sashes 30 slidably mounted in sash channels of a window frame, comprising a supporting frame for attaching the sash holder to a sash, a friction shoe 35 movably mounted on said supporting frame at one edge thereof and freely shiftable laterally of the supporting frame in either direction so as to project more or less beyond the frame for frictional engagement with a wall of the sash channel in which the sash is slidably mounted, said shoe being freely pivotal about its mid-point so as to be automatically self-aligning with the wall of the sash channel which it engages, and means 40 for controlling the movements of said friction shoe so that the friction shoe normally tends to bind or wedge against the wall of the sash channel aforesaid to resist sliding movement of the sash in one direction, and tends to release the binding or wedging action on movement of the 45 sash in the opposite direction.

6. A window sash holder as defined in claim 5, wherein the means for controlling the movements of the friction shoe includes a member 50 pivotally connected at a fixed point to the supporting frame and connected to said friction shoe.

7. A window sash holder as defined in claim 5, wherein the means for controlling the movements of the friction shoe includes a link having 55 a fixed pivotal connection at one end to the supporting frame and pivotally connected at its other end to the friction shoe.

8. A window sash holder as defined in claim 5, wherein the means for controlling the movements of the friction shoe includes a link pivotally connected at one end to the supporting frame and pivotally connected at its other end to the friction shoe, said link being of such length that the distance along the central axis of the link from the point of pivotal connection of the same 60 with the supporting frame to the sash channel wall engaging edge of the friction shoe is always greater than the shortest distance from said pivotal point to the shoe-engaging wall of the sash channel.

9. A window sash holder as defined in claim 5, wherein the means for controlling the movements of the friction shoe includes a spring-pressed member pivotally connected on a fixed pivot to the supporting frame and connected to said 70 friction shoe.

10. A window sash holder as defined in claim 5, wherein the means for controlling the movements of the friction shoe includes a member pivotally carried by the supporting frame and connected to said friction shoe, and stop means coacting with said shoe for limiting movement of the friction shoe in one direction.

11. A window sash holder as defined in claim 5, wherein the means for controlling the movements of the friction shoe includes a member pivotally carried by the supporting frame and connected to said friction shoe, and adjustable stop means coacting with said shoe for limiting movement of the friction shoe in one direction.

12. A holder attachment for closures slidably mounted in guide channels, comprising a frame plate having means at one end for attaching the same to the closure, a pair of friction shoes carried by the frame plate at its opposite side edges and projecting beyond the edges of said frame plate for frictional engagement with the opposite faces of the guide channel in which the closure is slidably mounted, one of said friction shoes being fixed, and the other of said shoes being movable in opposite directions about a fixed center so as to permit movement of the same towards and away from the fixed shoe, yieldable means for normally urging the movable shoe away from the fixed shoe, and means for limiting the latter movement.

13. A holder attachment as defined in claim 12, wherein the fixed center of the movement of the movable shoe lies approximately at the center of the fixed shoe.

14. A holder attachment as defined in claim 12, wherein the respective shoes are each elongated in the direction of the guide channel to provide friction surfaces of substantial area at the outer faces thereof.

15. A holder attachment as defined in claim 12, wherein the respective shoes are each elongated in the direction of the guide channel to provide friction surfaces of substantial area at the outer faces thereof, and the movable shoe is free to self-align itself in parallel relation to the fixed shoe in all positions of movement of the former.

16. A holder attachment as defined in claim 10 12, wherein the means for limiting movement of the movable shoe away from the fixed shoe comprises a screw member carried by the frame plate.

17. A holder attachment as defined in claim 15 12, wherein the means for limiting movement of the movable shoe away from the fixed shoe comprises a screw member carried by the frame plate and threadedly engaged with the frame plate for adjustable abutting contact with the movable shoe.

18. A holder attachment as defined in claim 12, wherein the means for limiting movement of the movable shoe away from the fixed shoe comprises a screw member carried by the frame plate and loosely extended therethrough and into adjustable threaded engagement at one end with the movable shoe, the opposite end of the screw member having a shoulder for abutting engagement with the frame plate.
